FOLDING DISPLAY CONTAINER

Oscar J. Towell, Chicago, Ill., assignor to Bunte Brothers, Chicago, Ill., a corporation of Illinois

Application October 1, 1934, Serial No. 746,277

14 Claims. (Cl. 229—41)

This invention relates to folding display containers, and its primary object is to provide a new and novel folding display container which is made in two pieces cut from a blank, which 5 is provided with a hinged bottom so that the bottom can be easily and readily folded along the hingedly connected bottom between the hinged sides of the container, and which is provided with new and novel reinforcing means to support the 10 bottom whereby the container is adapted to carry relatively heavy articles.

Other objects of the invention consist in the provision of features pertaining to the manner of fastening the hingedly connected sides, the interlocking feature of the bottom with the sides, the reinforcing means for supporting the bottom to carry heavy articles, the manner of scoring the sides to permit the container to be folded into a relatively small package, the fastening of the 15 bottom and sides, and the general form, arrangement and construction of the container itself and the parts which form the container.

Numerous other objects and advantages will 20 be apparent throughout the progress of the following specification.

The accompanying drawings illustrate selected 25 embodiments of the invention, and the views therein are as follows:

Fig. 1 is a perspective view of one form of container.

Fig. 2 is a plan view showing the parts constituting the container and as cut from a blank.

Fig. 3 is a bottom plan view.

Fig. 4 is a top plan view of the container partly 30 folded.

Fig. 5 is a transverse sectional view on the line 35 5—5 of Fig. 4.

Fig. 6 is a detail top plan view, partly in section, on the line 6—6 of Fig. 7, showing the container in folded or collapsed position.

Fig. 7 is a front elevation of the container in folded or collapsed position.

Fig. 8 is a detail elevational view showing the 40 manner in which the side sections are fastened together, also the manner in which the bottom reinforcement may be formed and fastened.

Fig. 9 is a detail sectional view showing the bottom construction and the locking tabs or ears.

Fig. 10 is a detail sectional view on the line 45 10—10 of Fig. 16 showing the bottom construction of the modified form of container shown in Fig. 11; also the locking ears or tabs as employed on the modified forms of container shown in Figs. 50 11 and 15.

Fig. 11 is a detail perspective view showing a modified form of container.

Fig. 12 is a plan view showing the parts constituting the container shown in Fig. 11, and as 5 cut from a blank.

Fig. 13 is a bottom plan view of the container shown in Fig. 11.

Fig. 14 is a front elevation of the container shown in Fig. 10 in collapsed or folded position.

Fig. 15 is a detail perspective view of another 10 modified form of container.

Fig. 16 is a detail sectional view on the line 15 16—16 of Fig. 15 showing a different bottom arrangement but employing the locking ears or tabs of the container shown in Fig. 11.

Referring to the drawings, and particularly Figs. 1 to 9 thereof, the container comprises a back 1 which merges with the upwardly extending card or part 2 of the back. The back is scored along the lines 3 and 4 to provide rear hingedly connected sides or sections 5, 6, and 7. The score lines 3 and 4 extend upwardly a predetermined distance to a point indicated by the numeral 8 which coincides with the long score line 9. The upper portion 2 of the back 1 has no score lines 25 provided therein above the score line 9; thereby a tension is created or exerted on the part 2 when the container is in extended position. This construction assists in holding the container, or at least the part 2, in extended or expanded rigid 30 position. A bottom 10 is formed integrally with the back 1 and is provided with a score line 11 whereby the bottom is hingedly connected to the back 1. The connection of the bottom to the back, in the embodiment shown, is substantially 35 equal to the distance between the score lines 3 and 4.

The front 12 of the container is scored along the lines 13, 14, 15, and 16, to provide the front sides or sections 17, 18, and 19, and the attaching 40 flaps or tabs 20 and 21, respectively, all of which are integral with the front. The flap extensions 20 and 21 may be formed for fastening the front and back sections 1 and 12 together. These flaps may be locked to the cooperating part of the 45 structure in any convenient manner, such as by gluing or by the use of staples 22. Of course, it is to be understood that the flap sections 20 and 21 may be formed on the back section and fixed to the front section instead of being formed on 50 the front section and fastened to the back section as just described.

The bottom 10 may be of a size substantially 55 equal in area to the area of the bottom of the container at the place where the bottom is connected

to the back section or sides. This bottom is provided with a score line 23 whereby the bottom is adapted to be folded between the front and rear of the container. The free edge 24 of the container bottom 10 is adapted to be fastened to a flap 25, which may be formed integrally with the front side portion 18. This flap is scored at 26 and may be fastened to the bottom by gluing or by the use of staples 27, Fig. 3. In collapsing or folding the container, the bottom is pushed upwardly along the score line 23 whereby the inside of the front will move toward the inside of the back; the front section being movable toward the rear section, or vice versa, due to the score lines 13 and 16, Fig. 1. During this folding operation, the back and front will be flat, the score lines 13, 14, 15, and 16 of the front and the score lines 3 and 4 of the back permitting the container to acquire this flat folding operation and position.

To maintain the container in open or extended position and to assure the container of remaining in such position, integral flaps 28 and 29 are formed along certain edges of the bottom, and these flaps are adapted to have folding relationship with respect to the bottom, due to the score lines 30 and 31. When the container is in expanded position, the flaps 28 and 29 are adapted to assume a relatively vertical position and be received in the slots or keepers 32 and 33 to lock the parts together, as shown, Fig. 1. The flaps 28 and 29 engaging the recesses 32 and 33 formed in some of the enclosing side walls, have interlocking engagement with the side walls of the container. Therefore, when the container is in expanded position, the flaps cause the container to be maintained in expanded position and prevent unauthorized or accidental collapsing thereof. When it is desired to collapse the container, the bottom is merely pushed upwardly whereby the bottom will fold along the score line 23 and cause the flaps 28 and 29 to be released from their keepers 32 and 33. The container so far described is sufficiently strong for the display of certain articles. However, to sustain heavier articles and to prevent articles from falling through the spaces between the edges of the bottom and the sides of the container, and to make the container stronger and more rigid, bottom reinforcements are provided. These reinforcements strengthen and support the bottom, making the container capable of supporting and carrying devices or articles of considerable weight.

This bottom reinforcing means may comprise integral extensions 34 having integral attaching ears 35 which are adapted to be attached to a projection 36 formed on the enclosing sections or walls 5 and 7, Fig. 2. Each extension 34 is scored along the line 37 and is separated from the flaps 20 and 21 as indicated at 38, Figs. 2 and 3. The extension 34 is also scored along the line 39, therefore, each reinforcing section 34 is adapted to be folded in conformance with the folding operation of the container. Each section 34 is adapted to be fastened to the extension tab or flap 36, which is formed integral with the rear side sections 5 and 7 by stapling the ear 35 to the flap 36, the flap 36 being scored along the line 40 to permit proper folding of the bottom reinforcing means and the carton. The score lines 39 and 40 permit the reinforcing member or projections 34 and 36 to be folded or bent at right angles to the wall sections, while the score lines 37, which coincide with the bottom score line 23 when the carton is folded, permit the reinforcing means 34, 35, and 36 to be folded. When the reinforcing

means 34 is folded inwardly, the score line 36 will coincide with score lines 13 and 16.

The bottom reinforcing means 34-36 is adapted to reinforce the bottom at each side of the container at the end of the score line 23. Each 5 of the side reinforcing means is provided with a scoreline to permit the reinforcing extension to be folded upwardly into the container or to project outwardly therefrom. When the container is folded, the score line 37 will be exactly opposite 10 and coincidental with a score line 13 or 16. Therefore, when the container is in extended position, the reinforcing member will lie flat and support the flat bottom. When the container is collapsed, the bottom will fold upwardly along 15 the score line 23, while the reinforcing members 34-36 will move upwardly and inwardly or downwardly and outwardly, bending along the score lines 37, 39, and 40 and be arranged in between the front 12 and the back 1. As the container is 20 collapsed, the edges of the container, defined by the score lines 13 and 16, will move or spread outwardly, permitting free movement and operation of the reinforcing means 34-36 either upwardly or downwardly. When the container is 25 to be moved from collapsed to extended position, the reinforcing members will move to straight or horizontal position and receive and support the bottom. The bottom, therefore, is considerably or materially reinforced, permitting the 30 container to support and carry relatively heavy objects and at the same time prevent the objects or articles in the container from falling through between the bottom edge of the container and the bottom. The extension ear 35 is fastened to 35 and locked with the extension 36 which extends down from the bottom of the container from a side section, the portion 35 being fastened to the extension 36 by means of a staple 41, Figs. 3 and 8.

The reinforcing construction just described 40 permits the flaps 20 and 21 and the extensions 35 and 36 to be stapled together by a straight stapling operation, that is, all the staples 22 and 41 are in alignment, and these attaching edges of the container can be easily run through the 45 stapling machine without the necessity of turning the container or moving its relative position during the fastening of the front and back together, Fig. 8.

To permit the container to be folded in a 50 collapsed package to permit the same to be inserted in a compact form in a box of candy, means are provided to provide additional fold in the container whereby the distance across the container from the score lines 13 to 16 can be 55 materially shortened. This is accomplished by providing score lines 42 and 43 in the back sections 5 and 7 and score lines 44 and 45 in the front sections 17 and 19 respectively. Therefore, when the container is being folded or collapsed, 60 the container will first assume the position shown in Fig. 5 until the score lines 44 and 45 are substantially adjacent or face to face with score lines 42 and 43 respectively. The ends of the carton outwardly from the edges of the score 65 lines 42 and 44 and 43 and 45 are then turned rearwardly as indicated in dotted lines in Fig. 6. Further folding movement of these end sections, which are indicated by the numeral 46, permits these end sections to lie flat against the rear 70 side of the back 1 as indicated in full lines in Fig. 6 and, therefore, when these end sections 46, which extend beyond the score lines 42, 44 and 43, 45 are folded against the rear surface of the back 1 and the display card 2 on the back 75

1 is folded downwardly, as clearly shown in Figs. 6 and 7, a very small and compact carton is provided. This carton can, therefore, be easily arranged in a relatively small candy package and shipped right along with the goods. In extending the container from the position shown in full lines in Figs. 6 and 7, to its expanded position shown in Fig. 1, the display card is first raised upwardly and the end sections 46, which comprise substantially half of the side sections 5, 17 and 7, 19, are pulled outwardly until the card assumes the position shown in Fig. 4. The bottom 10 is then pushed downwardly, pressure being exerted along the score line 23. The side sections or end closing wall of the container will then be expanded and the locking ears or tabs 28 will be received in their complementary keepers 32. The carton is thus maintained in proper expanded rigid position and maintained in that position. The device is so constructed that when the bottom is pushed down and the parts are arranged in their proper expanded and locked position, the container will lie flat on its bottom and will not tip. The reinforcing elements 34 and 36 on the bottom support and strengthen the bottom. In order, however, to permit the end portions 46 to be bent around the coinciding score lines 42, 44 and 43, 45, it is necessary that the front 12 be made slightly longer than the back 1. In order to give the container a symmetrical appearance, the additional length of the front is taken up in the sections 17 and 19. In other words, the central front side wall 18 is exactly the same size as the central rear side wall 6, but the side front walls 17 and 19 are a little greater in length than the side rear walls 5 and 7. However, the length of the front section is only increased a length sufficient to permit the material to fold around the folding axes indicated by the numeral 47 in Fig. 6.

In Figs. 10 to 14 inclusive a slightly different type of container is shown. This latter container may or may not have the additional fold lines 42, 44 and 43, 45, if desired. However, the carton is shown as not having these additional fold lines. The difference between this latter type of container and the one previously described consists in the locking tab and the bottom reinforcement. Also, the container is being shown as having a display card on the back which is not provided with a score line 9, but it is, of course, readily understood that the display card portion 2 of the back can be increased and the score line 9 provided therein. In the carton shown in Figs. 5 to 14 inclusive the bottom 10 is provided with flaps 50. Along the edges 51 thereof, Fig. 12, integral locking ears 52 are formed on the tabs 50. These tabs are adapted to be engaged and received in keepers 53 which may be in the form of notches or slots provided in the enclosing side walls 5 and 7. Also, instead of providing the attaching flaps 36 as previously described, the reinforcing means 54 are connected solely to the front section 12. These reinforcing means 54 are attached to the enclosing wall sections 17 and 19 and inasmuch as both reinforcing means 54 are exactly alike, only one will be described. For the purposes of simplification, the reinforcing means 54, as attached to the section 17, will be described. The reinforcing means 54 on the section 17 comprises an integral portion 55 which is scored along the lines 56, 57, and 58. The parts 56 and 57 comprise the bottom reinforcement, the score line 57 being provided only for the purpose of permitting the folding of the reinforcement 54. This score

line 57 will coincide with the score line 23 in the bottom and for all intents and purposes is the same as the score line 37 described in the embodiment shown in Figs. 1 to 9. The score line 58 is for the same purpose as the previously described score line 39. However, the integral portion 55 is separated from the flap 20 by a slit 59, thereby providing an attaching flap 60. This attaching flap 60 is adapted to be received between an outer edge of the back and the flap 20, extending upwardly substantially vertically with its edge 61 engaging the score line 13. When the attaching flap 60 is fixed in position between the rear side of the back and the inner side of the flap 21, such as by gluing or stapling, the reinforcement 54 will be flat, providing surfaces to reinforce and support the bottom 10, also the score line 57 will be in alignment and coincidental with the score line 23 in the bottom. The score lines 56 and 58 will be at the bottom edge of the side walls of the container, thereby permitting the reinforcement 54 to be folded upwardly and inwardly of the carton. The carton, in its extended position, is shown in Fig. 11. When it is desired to collapse the carton to the position shown in Fig. 1, the bottom is pressed upwardly along the score line 23, whereby the bottom will be arranged between the front 12 and back 1. Such movement causes the reinforcement 54 to hinge on the score lines 56, 57, and 58. When in collapsed position, the score line 57 will move toward the score line 13. To extend the container from its folded position shown in Fig. 14 to its extended or expanded position shown in Fig. 11, all that is necessary is to push downwardly on the bottom 30 whereby the bottom and reinforcing means will flatten out and the ears 52 will engage the respective keepers 53, the flaps 50 closing the space between the bottom edge of the side walls and the bottom. The container shown in Figs. 10 to 14, therefore, has one side of the bottom connected to the front side of the wall section 18 and hinged thereto. The rear side of the bottom is hingedly connected with the central back section 6. The front sides of the container rest upon the reinforcements 54. The back sides of the container have the upwardly extending flaps 50, whereby there will be no opening between the top of the bottom and the lower edge of the side walls to permit articles to accidentally fall out of the container.

In the modification shown in Figs. 15 and 16, the bottom reinforcement may be the same as that described relative to Figs. 10 to 14, but employing a different bottom construction. In these latter views the bottom comprises two parts 70 and 71. The section 70 is substantially the same size as the bottom of the container in its expanded condition and its front edge is provided with a tab or locking ear 72 which is adapted to extend through a slot 73 provided in the front side of the container. The flap 71 is hingedly connected to the front section 18 of the container and has a tongue 74 which is adapted to stick into the slit 75 provided in the main bottom structure 70. Therefore, the folding operation of the container shown in Figs. 16 and 17 is the same as that described relative to Figs. 10 to 14 inclusive. Instead of having the score line 23, however, the bottom, which comprises two parts 70 and 71, each of which is hingedly connected to a part of the container as indicated at 76 and 77, is adapted to be folded within the front and back of the container. Thus, during the folding movement to collapse the container, the parts 70 and 75

71 will move upwardly along their hinge line, the part 71 being first detached from the part 70 by pulling the tongue 74 out of the slit 75 and the part 70 being detached from the front of the container by pulling the flap 72 out of its slot 73. This construction provides a reinforced bottom because the tongue 75 which is integral with the bottom portion 71, extends through the slit and extends in the inside of the container and rests 10 upon the portion 70 as clearly indicated in Fig. 16. The means for reinforcing the bottom may be the same as those previously described, Figs. 15 and 16, showing the flap and ear construction 50 and 52. The bottom reinforcement may also be of 15 either type previously described, but the figures show the reinforcing means 36 as described relative to Figs. 1 to 9 inclusive.

Fig. 10 specifically shows an adaptation of the 20 interlocking means of Figs. 11 to 14 and the bottom reinforcing means shown and described relative to Figs. 1 to 9. In other words, this figure shows the interlocking means shown in Figs. 11 to 14 and the reinforcing means shown in Figs. 1 to 9.

25 Each of the containers herein shown is multi-sided, being in the form of a hexagon in horizontal cross section. The container is preferably made wider at the top than it is at the bottom, being in the form of a frusto-pyramid. 30 Each of the containers herein described permits proper folding thereof so that the container, when in collapsed position, will be relatively compact and require very little space. The containers are strong and durable in construction, preferably being 35 made from cardboard or other similar material. The score lines provide hinged connected sides and permit the containers to be readily and quickly folded in collapsed position, and the containers can be readily extended from 40 collapsed position. Each container provides means for securely locking the parts together and for amply reinforcing the bottom of the container so that it may be used for carrying and holding relatively heavy objects. While the 45 containers are primarily for holding, showing and advertising candy bars, they are equally applicable for displaying soaps, canned goods, bottled goods and many other articles.

The term "carton" herein used is to be given its 50 broadest interpretation and includes baskets, boxes and all other receptacles capable of holding and displaying various forms of articles.

Changes may be made in the form, construction, and arrangement of the parts without departing from the spirit of the invention or sacrificing any of its advantages, and the right is hereby reserved to make all such changes as fairly fall within the scope of the following claims.

The invention is hereby claimed as follows:

60 1. A container comprising a plurality of hinged connected sides, a bottom integrally formed with and hinged connected to a part of the container, said bottom being provided with a hinge line to permit the bottom to be folded between the front and rear of the container, and a reinforcing element integral with one of the sides of the container and extending across a part of the bottom and connected to another of the sides of the container to support the container bottom, said bottom, said reinforcing element being provided with hinge lines at edges of the container and with a central hinge line whereby the reinforcing means may be folded during collapsible movement of the container, said bottom having a radius of swing 75 and said reinforcing element having a radius of

swing shorter than the first named radius whereby to cause the reinforcing element to move downwardly into bottom supporting position ahead of the bottom when the container is being unfolded.

2. A folding display container comprising a plurality of downwardly converging sides and a foldable bottom, and reinforcing means connected to the sides and extending under the side edges of the bottom to support the foldable bottom when the container is in expanded position, said bottom having a radius of swing and said reinforcing means having a radius of swing shorter than the first named radius whereby to cause the reinforcing means to move downwardly into bottom supporting position ahead of the bottom when the container is being unfolded. 10

3. A folding display container comprising a plurality of hexagonally disposed downwardly converging sides and a foldable bottom, and reinforcing means connected to the container and 20 extending under the bottom side edges thereof to support the foldable bottom when the container is in expanded position, said reinforcing means being provided with a plurality of score lines whereby the reinforcing means may be 25 folded when the container is folded, said bottom having a radius of swing and said reinforcing means having a radius of swing shorter than the first named radius whereby to cause the reinforcing means to move downwardly into bottom 30 supporting position ahead of the bottom when the container is being unfolded.

4. A container comprising a plurality of hinged connected side walls, a bottom hinged connected to a front and rear side wall, said bottom being provided with a hinge line whereby the bottom may be folded during collapsible movement of the container, flaps extending upward from certain edges of said bottom and adapted to be lockingly received in certain side walls of the container, and reinforcing means arranged across the bottom edges of the side walls and adapted to support the container bottom, said bottom having a radius of swing and said reinforcing means having a radius of swing shorter than the first named radius whereby to cause the reinforcing means to move downwardly into bottom supporting position ahead of the bottom when the container is being unfolded. 40

5. A container comprising a plurality of hinged connected side walls, a bottom hinged connected to a front and rear side wall, said bottom being provided with a hinge line whereby the bottom may be folded during collapsible movement of the container, flaps extending upward from certain edges of said bottom and adapted to be lockingly received in certain side walls of the container, and reinforcing means arranged across the bottom edges of the side walls and adapted to support the container bottom, said bottom having a radius of swing and said reinforcing means having a radius of swing shorter than the first named radius whereby to cause the reinforcing means to move downwardly into bottom supporting position ahead of the bottom when the container is being unfolded. 50

6. A container comprising a plurality of hinged connected side walls, a bottom hinged connected to a front and rear side wall, said bottom being provided with a hinge line whereby the bottom may be folded during collapsible movement of the container, flaps extending upward from certain edges of said bottom and adapted to be 60

lockingly received in certain side walls of the container, and reinforcing means arranged across the bottom edges of the side walls and adapted to support the container bottom, said reinforcing means being integral with the side walls and having a hinged connection therewith, said reinforcing means also being provided with score lines whereby the reinforcing means may be folded during folding movement of the container, said bottom having a radius of swing and said reinforcing means having a radius of swing shorter than the first named radius whereby to cause the reinforcing means to move downwardly into bottom supporting position ahead of the bottom when the container is being unfolded.

7. A container in the form of a hexagonal frusto-pyramid comprising a front and a back each cut from a blank of flexible material, the front and back each having vertical score lines therein at intervals to form a series of panels constituting the side walls of the box, the front and back adapted to be connected together, there being score lines at the connection to provide a hinge joint between the front and the back, a hexagonal-shaped bottom having one of its sides hingedly connected to the back of the container and its opposite side hingedly connected to the front of the container, said bottom having its other ends free, a score line arranged intermediate the back and front hinge connection of the bottom whereby the bottom may be folded between the front and back of the container, and bottom reinforcing means secured to the side walls for supporting the bottom, said bottom having a radius of swing and said reinforcing means having a radius of swing shorter than the first named radius whereby to cause the reinforcing means to move downwardly into bottom supporting position ahead of the bottom when the container is being unfolded.

8. A container in the form of a hexagonal frusto-pyramid comprising a front and a back each cut from a blank of flexible material, the front and back each having vertical score lines therein at intervals to form a series of panels constituting the side walls of the box, the front and back adapted to be connected together, there being score lines at the connection to provide a hinge joint between the front and the back, a hexagonal-shaped bottom having one of its sides hingedly connected to the back of the container and its opposite side hingedly connected to the front of the container, said bottom having its other ends free, a score line arranged intermediate the back and front hinge connection of the bottom whereby the bottom may be folded between the front and back of the container, and bottom reinforcing means secured to the side walls for supporting the bottom, said bottom reinforcing means being provided with hinge joints whereby the reinforcing means may be folded during folding operation of the container, said bottom having a radius of swing and said reinforcing means having a radius of swing shorter than the first named radius whereby to cause the reinforcing means to move downwardly into bottom supporting position ahead of the bottom when the container is being unfolded.

9. A container comprising a pair of sheets each including a plurality of hingedly connected sections, said sheets being secured together at their ends to form a plurality of hingedly connected continuous side wall container sections, a bottom substantially commensurate with the opening at the lower edges of said side wall sections hingedly

connected to one of said sections, and extensions hingedly connected to the side wall sections adjacent the line of juncture between said sheets and underlying portions of the bottom whereby to support the bottom.

10. A container comprising a pair of sheets each including a plurality of hingedly connected sections, said sheets being secured together at their ends to form a plurality of hingedly connected continuous side wall container sections, a bottom substantially commensurate with the opening at the lower edges of said side wall sections hingedly connected to one of said sections, and an extension integral with the side wall section at the end of one of said sheets and secured to the side wall section at the end of the other of said sheets and underlying the adjacent portion of the bottom whereby to support the bottom.

11. A container comprising a plurality of hingedly connected side walls, a bottom comprising a pair of members each hingedly connected to one of said side walls, one of said members having an opening through which a portion of the other of said members extends whereby said members are secured together, and extensions secured to said side walls and bridging said walls underneath opposite portions of the bottom whereby to support the bottom.

12. A container comprising a pair of sheets each including a plurality of hingedly connected sections, means for securing the ends of said sheets together to form a continuous polygon of side wall container sections, a bottom member hingedly secured to one of said side wall sections, said bottom member being scored along the center line thereof whereby to permit collapse of the bottom and collapse of the side wall sections, reinforcing means secured to the side walls and underlying the bottom across the score line thereon, said reinforcing means being scored in line with the scoring on the bottom whereby said reinforcing means may be collapsed with the bottom, and the wall sections adjacent the ends of the sheets being scored to permit the further collapse and folding of the side wall portions whereby to render the folded container more compact.

13. A container comprising a plurality of hingedly connected sides, a bottom hingedly connected to the container at one side thereof, said bottom being provided with a hinged joint to permit the bottom to be folded between a front and rear side of the container, and a reinforcing element connected to a part of the container and extending across the lower edge thereof to support the bottom when in unfolded condition, said bottom having angularly disposed extending portions overlying lower inner portions of the container sides and in the plane of the bottom.

14. A container comprising a plurality of hingedly connected side walls, a bottom comprising a pair of members each hingedly connected to one of said side walls, one of said members having an opening through which a portion of the other of said members extends whereby said members are secured together, extensions secured to said side walls and bridging said walls underneath opposite portions of the bottom whereby to support the bottom, and locking means integrally formed with the bottom upstanding from the plane thereof, engageable with the side of the container whereby to lock the bottom in opened-down position.

OSCAR J. TOWELL.
